UNITED STATES PATENT OFFICE

JAMES H. RAND, JR., OF TONAWANDA, NEW YORK, ASSIGNOR, BY MESNE ASSIGNMENTS,
TO REMINGTON RAND INC., OF NEW YORK, N. Y., A CORPORATION OF DELAWARE

CARD INDEX

Application filed December 12, 1922. Serial No. 606,444.

This invention relates to card index or record devices and more particularly to card-retaining or index data displaying sheaths for devices of this kind.

Heretofore index and record devices have been provided consisting of card-holders provided with sheaths at their lower edges for receiving an edge of a card to be supported thereon, means being usually provided at the upper portion of the holder for engaging the upper edges of the cards. These sheaths are usually transparent so that index data or material on an edge of the card may be viewed therethrough, or for the purpose of displaying a suitable label slip or the like. Cards have also been provided with similar transparent sheaths on their edges adapted to receive and display a label or designation slip. In devices of this character it has been difficult at times to retain the cards or slips in position in the sheaths. In the case of the card holders, while the holder remains substantially flat and while the card is adequately secured at the top, it may be maintained in position, but in case the top securing means release or in case the holder is bent excessively, the lower edge of the card is likely to slip out of the sheath. Furthermore, with the sheaths as heretofore constructed, difficulty has attended rapid and ready insertion of the cards or labels in the sheaths, due to the fact that the upper edge of the sheath will not always lie in a straight line, or will tend to adhere to the holder, and this oftentimes requires considerable manipulation of the card or slip to effect a proper insertion in the sheath.

The objects of the present invention are to provide improvements in these devices whereby the card may be readily inserted in the sheaths; also to provide devices of this character in which the cards or slips are securely held in the sheaths against unintentional displacement; also to provide improvements in devices of this type in the other respects hereinafter set forth and claimed.

In the accompanying drawings:

Fig. 1 is a plan view of a card-holder and card embodying the present invention.

Fig. 2 is a sectional perspective view on line 2—2, Fig. 1, on an enlarged scale.

Fig. 3 is a portion of a perspective view thereof.

Figs. 4 and 5 are portions of a sectional perspective view illustrating the manner in which the card enters the sheath. 55

Fig. 6 is a sectional perspective view on line 6—6, Fig. 1, on an enlarged scale.

Fig. 7 is a section on line 7—7, Fig. 1, 60 on an enlarged scale.

Fig. 8 is a portion of a plan view of a modification thereof.

Fig. 9 is a sectional perspective view on line 9—9, Fig. 8, on an enlarged scale. 65

Fig. 10 is a section on line 10—10, Fig. 11.

Fig. 11 is a section on line 11—11, Fig. 8.

The embodiment of the invention illustrated includes, generally, a member having a sheath for receiving an edge of a card or slip and means for closing the sheath to retain the card in the sheath, the sheath being so formed that it facilitates ready insertion of the card or slip. 70

In Figs. 1 to 7 of the drawing, 10 designates 75 a holder or member provided with a sheath 11 forming a pocket on the face of the holder, which is adapted to receive an edge of a card 12 or any other suitable index or record insert. The sheath 11 is preferably formed of suitable 80 transparent material, such for example, as celluloid, whereby index matter on the edge of the card or other insert beneath the sheath may be readily viewed. The sheath may be attached to the holding member by any suitable means, such for example as staples 13.

In order that the sheath 11 may securely hold the cards or other inserts therein, it is preferably formed with a part or parts normally offset from its front side and preferably resiliently tending to contact with the holder, thereby permitting free insertion of a card or index slip and effectually preventing unintentional removal of the card or slip. In the embodiment shown the sheath is formed with an inwardly offset rib 14 which is adapted to bear against the face of the holder or member 10. The body of the sheath being constructed of celluloid or other suitable resilient material, 95 this rib is maintained resiliently in contact

with the holder or with a card or the like inserted in the sheath, thereby tending to prevent unintentional removal of the card or slip from the sheath.

5 In order to facilitate insertion of a card or other member into the pocket, the upper edge 15 of the sheath is formed to extend angularly from the face of the member 10. This formation of the rib and of the angularly extending 10 edge of the sheath renders the sheath more rigid at its upper or free edge, prevents buckling or distortion of the sheath and at the same time facilitates the insertion of a card or other member into the pocket. This rib 15 forms a shoulder which tends to retain the insert in the pocket.

For the purpose of cooperating with the resilient gripping portions on the sheath, the card or other insert may be provided with 20 suitable means for engaging the gripping portions of the sheath to more firmly retain the card in position in the sheath. For this purpose, in the embodiment illustrated, there is shown a projection, bead, or embossment 16 protruding at one face of the card. As illustrated in Fig. 6, this projection engages beneath the rib or shoulder on the sheath when a card has been inserted in the pocket and cooperates with that gripping means and resiliently prevents the card from being accidentally removed from the pocket.

In the form of the invention illustrated in Figs. 8 to 11 inclusive, there is shown a substantially double locking of the card or other member in the pocket. In this form the holder member 10^a is provided with a suitable opening or aperture 17 the sides and upper edge of which form vertical and horizontal shoulders and an embossment or protuberance 18 is provided on the rear side of the card 19. This embossment or protuberance enters the opening or aperture 17 when the card is inserted in the pocket and engages the shoulders formed by that opening in order to prevent movement of the card in vertical and transverse directions. The resilient engaging member 20 of the sheath presses against the card and holds the boss or protuberance 18 in the aperture 17 and beneath the horizontal shoulder formed thereby thus preventing any accidental movement of the card outwardly from the face of the holder member.

As is usual in devices of this kind, the holder member illustrated may be used to support a card upon which index or record matter appears, or a portion or all of the index or record may be directly written or imposed upon the so-called holder and the pocket used to retain a smaller card or an index or reference slip.

60 I claim as my invention:

1. A holder having a pocket provided with a resilient offset portion, a card adapted to be inserted in said pocket and to be frictionally engaged by said resilient offset portion, and a protuberance on a face of said card engaged

in the pocket for engaging said offset portion of the pocket to releasably secure said card in the pocket.

2. A holder member, a transparent sheath forming a pocket on said holder member adapted to receive an insert member, and comprising an inwardly projecting part for pressing said insert member against said holder member, and a pressed bead on said insert member adapted to interlock with said inwardly extending pocket part for releasably holding said insert member in said pocket.

3. A holder having a pocket provided with an offset portion, a card adapted to be inserted in said pocket and to be frictionally engaged by said offset portion, a projection on said card adapted to cooperate with said offset portion to releasably secure said card in said pocket, and said pocket having an edge portion projecting outwardly at an angle to the face of said holder and adapted to guide the edge of said card and projection into said pocket.

4. A holder member having a pocket-forming member embracing a marginal portion thereof, said pocket member having a portion resiliently projected toward said holder member, card retaining means on said portion, a card adapted to be inserted in the pocket formed by said members and to be frictionally engaged by said card, card-retaining means, and a projection on said card adjacent its marginal portion adapted for interlocking cooperation with said card retaining means.

5. A holder comprising a pocket, an insert member adapted to be received in said pocket, an integral relatively small projecting boss on said insert member, and an integral straight, substantially continuous projection on said holder for engaging with said boss on said insert member to releasably hold said insert member in said pocket.

6. A holder comprising a back member and a front member yieldably urged toward one another, a card adapted to be inserted between said members, a boss on said card, and a shoulder provided on one of said members for engagement over said boss to prevent vertical displacement of said card from said holder.

JAMES H. RAND, JR.

CERTIFICATE OF CORRECTION.

Patent No. 1,774,238.

Granted August 26, 1930, to

JAMES H. RAND, JR.

It is hereby certified that error appears in the printed specification of the above numbered patent requiring correction as follows: Page 2, line 97, claim 4, strike out the word "card" first occurrence; and that the said Letters Patent should be read with this correction therein that the same may conform to the record of the case in the Patent Office.

Signed and sealed this 28th day of October, A. D. 1930.
